UNITED STATES PATENT OFFICE

DAVID STROMBERG, OF CLEVELAND, OHIO

DESIGN FOR A BUILDING

Application filed October 9, 1930. Serial No. 37,200. Term of patent 14 years.

To all whom it may concern:

Be it known that I, DAVID STROMBERG, a citizen of the United States, residing at Cleveland, in the county of Cuyahoga and State of Ohio, have invented a new, original, and ornamental Design for a Building, of which the following is a specification, reference being had to the accompanying drawing, forming a part thereof.

In the drawings, Fig. 1 is a side elevation of a building embodying my invention, and Fig. 2 is a front elevation thereof.

I claim:

An ornamental design for a building, substantially as shown in the drawing.

DAVID STROMBERG.
